HENRY S. YOUNG, OF WILKINSBURG, PENNSYLVANIA, ASSIGNOR TO THE UNION
SWITCH & SIGNAL COMPANY, OF SWISSVALE, PENNSYLVANIA, A CORPORATION
OF PENNSYLVANIA

ELECTRICAL CONTROLLING APPARATUS

Original application filed May 7, 1927, Serial No. 189,614, Patent No. 1,744,821 dated January 28 1930.
Divided and this application filed November 9, 1929. Serial No. 405,954.

My invention relates to electrical controlling apparatus and particularly to apparatus for controlling an electric motor such as a railway switch operating motor or the like, 5 from a remote point.

The present application is a division of my copending application, Serial No. 189,614, filed May 7, 1927, for electrical controlling apparatus.

10 I will describe one form of apparatus embodying my invention and will then point out the novel features thereof in claims.

The accompanying drawing is a diagrammatic view illustrating one form of apparatus embodying my invention.

Referring to the drawing, the reference character A designates a railway switch of the usual and well known form, controlled by a motor M having an armature 1 and a field

20 2. Associated with switch A is a circuit controller E having a contact 3—4 which is closed at all times except when the switch occupies its reverse position, and a contact 3—5 which is closed at all times except when the switch occupies its normal position. The motor M is controlled by a manually operable lever L which may be one of a number of such levers located at a point remote from the switch, such for example, as in an interlocking cabin. As here shown, this lever is capable of assuming four positions indicated by dotted lines on the drawing, and designated by the reference characters N, B, D and R. The lever controls two NB contacts

30 which are closed for all positions of the lever between N and B, and two RD contacts which are closed for all lever positions between R and D.

It sometimes happens that the switch 40 which is to be controlled from the lever L is located at such a distance from the interlocking cabin which contains the operating lever that for reasons of economy and for other reasons it is not desirable to supply the operating energy for the switch motor M directly over line wires from the cabin. Under these conditions it is customary to provide a circuit controller located adjacent the switch and controlled by the lever L. This circuit controller in turn operates contacts which con-

trol the supply of energy from a local source to the switch operating motor M. Apparatus constructed in accordance with my invention for accomplishing this result is shown on the drawing. The lever L controls a circuit controller designated in general by the reference character S and comprising a magnetizable core 56 provided with a winding 57 and having an air gap in which is located a movable armature 58 provided with a second winding 59. The position of the armature 58 is responsive to the relative direction of the currents supplied to the windings 57 and 59. Operatively connected with the armature 58 are a pair of contact members 64 and 65 which co-operate with a plurality of fixed contacts as will appear hereinafter. As shown in the drawing the parts are all illustrated in the positions which they occupy when the switch lever L is normal and when the switch A occupies its normal position.

If, now, it is desired to reverse the switch A, the lever L is moved toward its reverse position, thereby closing the RD contacts on the lever. Current then flows from terminal X of a suitable source not shown in the drawing through an RD contact on the lever L, conductor 11, asymmetric unit 61, wire 67, winding 59, wire 66, asymmetric unit 63, contact 68—69 operated by circuit controller S, wire 70 winding 57, conductor 10, an RD contact on lever L and back to terminal Y of the same source. The current thus supplied to the windings 57 and 59 of circuit controller S causes operation of armature 58 to reverse the contacts 64 and 65. Current then flows from terminal X¹ of a local source adjacent the switch through wire 71, contact 72—73 of circuit controller S, wires 74 and 75, field

2 of switch operating motor M, wire 76, contact 77—78 of circuit controller S, wire 79, contact 3—4 of circuit controller E operated by switch A, wire 80, armature 1 of motor M, back to terminal Y¹ of the local source. Current flowing in this circuit causes operation of the motor M to move the switch A to its reverse position. When the switch has completed this movement the opening of contact 3—4 of circuit controller E interrupts the circuit for the motor. It should also be

observed that as soon as the circuit controller S is reversed, the supply of current to the windings 57 and 59 is discontinued by the opening of contact 68—69 so that this device does not consume energy except when the device is actually being operated to reverse the connections of the switch operating motor M.

In order to restore the switch to its normal position, the lever L is returned toward its N position to close contacts NB. Current then flows from terminal X through an NB contact on the lever, conductor 10, winding 57 of circuit controller S, wire 70, contact 81—82 of circuit controller S, wire 83, asymmetric unit 62, wires 84 and 67, winding 59 of circuit controller S, wires 66 and 85, asymmetric unit 60, conductor 11 and a second NB contact on the lever back to terminal Y. The current thus supplied to winding 59 of circuit controller S flows in the same direction as before through this winding, but the direction of flow of current in winding 57 is reversed. The circuit controller S is, therefore, reversed, opening contact 81—82 and discontinuing the supply of current to the circuit controller. The closing of contacts 86—87 and 89—90 completes a circuit over which current flows from terminal X¹, through contact 86—87, wire 76, field 2 of motor M, wires 75 and 88, contact 89—90, wire 91, contact 3—5 operated by switch A, wire 80, and armature 1 of motor M back to terminal Y¹. The motor M is, therefore, operated to restore the switch A to its normal position. When this movement of the switch has been completed, contact 3—5 opens and so disconnects the motor from its source of energy.

An indication relay K may be controlled jointly by contacts on the circuit controller S and by contacts operated by the switch A so that this relay can be energized only when the switch and the circuit controller S occupy corresponding positions. For example when the switch A and the circuit controller S both occupy their normal positions, in which they are shown in the drawing, current flows from terminal X¹, over contact 104—105 of the circuit controller S, wire 103, contact 99—102 operated by switch A, wire 98, winding of relay K, wire 97, contact 95—101 and back to terminal Y¹. If circuit controller S is reversed and if switch A also occupies its reverse position, relay K is energized in the other direction by current which flows from terminal X¹ over contact 92—93, wire 94, contact 95—96 operated by switch A, wire 97, winding of relay K, wire 98, contact 99—100 and back to terminal Y¹. It is understood, of course, that relay K in the drawing may be used to control a suitable lever locking device such as that disclosed in my co-pending application hereinbefore referred to.

Although I have herein shown and de-

scribed only one form of electrical controlling apparatus embodying my invention, it is understood that various changes and modifications may be made therein within the scope of the appended claims without departing from the spirit and scope of my invention.

Having thus described my invention, what I claim is:

1. In combination, two windings, a railway switch controlled in accordance with the relative direction of the currents supplied to such windings, two asymmetric units connected in series across one such winding, a first conductor connected with the common terminal of such two units, a second conductor; means controlled by the two windings for at times connecting the second conductor with one terminal of such one winding through the other winding and a third asymmetric unit, and for at other times connecting the second conductor with the other terminal of such one winding through the other winding and a fourth asymmetric unit; and a manually operable lever for reversibly supplying current to said conductors. 75 80 85 90

2. In combination, two windings, contact mechanism controlled in accordance with the relative direction of the currents supplied to such windings, two asymmetric units connected in series across one such winding, a first conductor connected with the common terminal of such two units, a second conductor; means controlled by said contact mechanism for at times connecting said second conductor with one terminal of such one winding through the other winding and a third asymmetric unit, and for at other times connecting the second conductor with the other terminal of such one winding through the other winding and a fourth asymmetric unit; a manually operable lever for reversibly supplying current to said conductors, and a railway switch controlled by said contact mechanism. 95 100 105 110 115

3. In combination, two windings, contact mechanism controlled in accordance with the relative direction of the currents supplied to such windings, two asymmetric units connected in series across one such winding, a first conductor connected with the common terminal of such two units, a second conductor; means controlled by said contact mechanism for at times connecting the second conductor with one terminal of such one winding through the other winding and a third asymmetric unit, and for at other times connecting the second conductor with the other terminal of such one winding through the other winding and a fourth asymmetric unit; a manually operable lever for reversibly supplying current to said conductors, a railway switch, a circuit controller controlled by said switch, and a motor controlled by 120 125 130

said contact mechanism and by said circuit controller for operating the switch.

4. In combination, two windings, contact mechanism controlled in accordance with the relative direction of the currents supplied to such windings, two asymmetric units connected in series across one such winding, a first conductor connected with the common terminal of such two units, a second conductor; means controlled by said contact mechanism for at times connecting the second conductor with one terminal of such one winding and a third asymmetric unit, and for at other times connecting the second conductor with the other terminal of such one winding through the other winding and a fourth asymmetric unit; a manually operable lever for reversibly supplying current to said conductors, a railway switch, a circuit controller controlled by said switch, a motor controlled by said contact mechanism and by said circuit controller for operating the switch, and locking means for said lever controlled by the contact mechanism.
- 25 5. In combination, two windings, contact mechanism controlled in accordance with the relative direction of the currents supplied to such windings, two asymmetric units connected in series across one such winding, a first conductor connected with the common terminal of such two units, a second conductor, means controlled by said contact mechanism for at times connecting the second conductor with one terminal of such one winding and a third asymmetric unit, and for at other times connecting the second conductor with the other terminal of such one winding through the other winding and a fourth asymmetric unit, a manually operable lever for reversibly supplying current to said conductors, a railway switch, a circuit controller controlled by said switch, a motor controlled by said contact mechanism and by said circuit controller for operating the switch, and locking means for said lever controlled by the contact mechanism and by the switch.

In testimony whereof I affix my signature.
HENRY S. YOUNG.
